United States Patent Office

Des. 220,670
Patented May 4, 1971

220,670

TIRE

Iain C. Mills, Sutton Coldfield, England, assignor to The
Dunlop Company Limited, Birmingham, England

Filed Feb. 20, 1970, Ser. No. 21,543

Claims priority, application Great Britain Aug. 28, 1969

Term of patent 14 years

Int. Cl. D12—14

U.S. Cl. D90—20

FIG. 1

FIG. 2

FIG. 3

FIG. 1 is a perspective view of the tire of my new design;

FIG. 2 is a fragmentary perspective view;

FIG. 3 is a fragmentary plan view.

The tread design shown is repeated throughout the circumference of the tire and the side opposite to that shown is the same.

I claim:

The ornamental design for a tire, as shown and described.
